United States Patent Office.

D. CYRUS HOLD RIDGE, OF LODI, WISCONSIN.

Letters Patent No. 70,844, dated November 12, 1867.

IMPROVEMENT IN TUBE-WELLS.

The Schedule referred to in these Letters Patent and making part of the same.

TO ALL WHOM IT MAY CONCERN:

Be it known that I, D. CYRUS HOLD RIDGE, of Lodi, in the county of Columbia, and State of Wisconsin, have invented certain new and useful Improvements in the Point of Iron Tubing for Wells; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to an improvement in the construction of the lower end or point of the iron tubing or shaft driven into soil suitable for the purpose of obtaining water. In the drawings—

Figure 1 represents a plan view of the point when arranged for being driven into the ground.

Figure 2 represents plan view of the point after being driven into the ground and ready to receive the water.

Figure 3 represents a transverse section on the line $x-x$ of fig. 1.

I construct the point B of wrought iron, of any required length and diameter, tapering or conical-shaped at the lower end c , and open at its upper end d . In this point I make two longitudinal key-slots C, on opposite sides of the point B, and having transverse continuations or notches e at their upper ends, as shown in figs. 1 and 2. In these figs. 1 and 2 the notches e are shown as turning only one way, but it is obvious they may be turned both ways. And in construction for practical operation I usually make them turned both ways. Within this point I place a screw, f, made of any suitable material, such as sheet iron or other metal of tubular form, and so as to move easily within the point B. This screw f, I provide with slots similar to those in the point B, but without any notches at their upper ends. After placing the screw f within the point B, I pass them over the end of the iron pipe A, which is of suitable size to allow them to work and turn easily upon it; and then pass an iron rod, g, transversely through them, and make a head, h, on either end, by riveting, or by means of a nut and screw, as shown in fig. 3. The portion of the bolt g between head h and the inner tube A may be either square, round, or oblong, and forms a nick made of suitable size to slide in the slots C and notches e. Now, when the heads h are on a line with the slots C in the point B, and in the screw f, the pipe A can be shoved down till the heads h reach the lower ends of the slots C, and when in that position the inner pipe A will entirely close the slots. After the point B has been driven as far into the ground as is desirable, the pipe or inner tube A may be drawn up till the heads h reach the upper end of the slots C, and then, by turning the pipe A, the screw f will turn with it, as there are no notches in it corresponding with those in the point B, and in turning, its perforated sides will be placed opposite the slots C in the point B, so that the water can pass readily through the screw f and into the pipe A. After the water enters the pipe A it can be pumped out. It is obvious that my improved point may be used in connection with the pipe A in open wells that fill up rapidly, as well as in sandy, marshy, or other light soils.

Having thus described my invention, what I claim is—

The tubular point B and screw f, in combination with the pipe A, when arranged to operate as described and for the purposes set forth.

D. CYRUS HOLD RIDGE.
